UNITED STATES PATENT OFFICE.

ELMER G. METCALF, OF CORTLAND, NEW YORK.

SUPPORTING-RACK.

1,162,298.

Specification of Letters Patent. Patented Nov. 30, 1915.

Application filed May 12, 1915. Serial No. 27,625.

To all whom it may concern:

Be it known that I, ELMER G. METCALF, a citizen of the United States, residing at Cortland, in the county of Cortland and State of New York, have invented certain new and useful Improvements in Supporting-Racks, of which the following is a specification, reference being had to the accompanying drawing.

10 My present invention relates to new and useful improvements in supporting racks and has particular reference to those of the type which are adapted especially for use in hanging laundry articles, such as towels, 15 garments or similar articles.

Primarily, the invention aims to provide an improved form of rack which is relatively simple in construction and may, therefore, be cheaply manufactured, and is 20 so designed that while it carries a relatively large number of supporting arms, these members are so arranged and related to each other that they may be folded to occupy a minimum space when the rack is 25 not in use.

A further and more specific object of the invention is to provide a novel form of supporting bracket for the shaft or axle upon which the arms of the rack are mounted and 30 to construct the bracket from a single length of wire, of relatively heavy gage.

The above, and other incidental objects of a similar nature, which will be hereinafter more specifically treated are accomplished 35 by such means as are illustrated in the accompanying drawings, described in the following specification, and then more particularly pointed out in the claims which are appended hereto and form part of this application.

With reference to the drawings, wherein there has been illustrated the preferred embodiment of this invention, as it is reduced to practice, and throughout the several views 45 of which similar reference numerals designate corresponding parts, Figure 1 is a side elevation showing the rack attached to a wall or similar supporting structure and disclosing the supporting arms in extended position; Fig. 2 is a top plan view of the rack as it is disclosed in Fig. 1; Fig. 3 is a detail perspective view of the supporting bracket in which the axle of the rack is mounted.

As embodied in the accompanying drawings, the rack includes generally, a supporting bracket 10, a shaft or axle 11 which

is supported thereby, a plurality of arms 12 which are swingingly attached to the shaft, and a plurality of spacing sleeves 13 which are disposed to maintain the supporting 60 arms in the proper spaced relation to each other.

The bracket above designated generally by the numeral 10 is formed from a single length of wire which is of relatively heavy 65 gage and is bent upon itself, at one terminal as shown in detail in Fig. 3 to produce an eye 14. This eye 14 is adapted to receive a screw or equivalent fastening device, whereby the upper end of the bracket is attached 70 to a door, wall or other supporting structure. After the upper terminal of the wire, forming the bracket has been bent to define the eye 14, it is directed downwardly along the body portion of the bracket for a slight 75 distance and is then bent laterally and at right angles to form a stub arm 15. The terminal of this stub arm is shaped to provide an eye 16 which is spaced outwardly 80 from the body of the bracket, as disclosed 85 in Fig. 3 so that the upper terminal of the shaft 11 may be journaled within the eye and spaced from the bracket. The lower end of the bracket forming wire is bent at right angles, as at 17.

At the terminal of the relatively short stub arm 17, is formed an eyelet 18, after which the wire is directed back along the portion 17, producing a portion 19. This portion 19 is of less length than the portion 90 17, so that an eye, indicated at 20 and formed on the outer end of a stub 21, which extends at right angles to the portion 19, may be disposed in alignment with the body 95 portion of the bracket. After the eye 20 is formed, the wire is rebent to form a stub arm similar to the stub arm 21 and is then bent at right angles to produce two arms 22 and 23 and an eyelet 24 similar to the members 17, 18 and 19.

It is now to be observed that the axle or shaft hereinbefore described by the numeral 11, is terminally journaled in the eyelets 16 and 20. Upon this shaft are mounted the terminal eyelets formed on the ends of the arms 12. The arms 12 are each formed from a single length of wire which is bent to form an upper section 25 and a lower section 26 on the terminals of which sections are formed the eyelets which embrace the 105 shaft. The lower sections of the arms extend upwardly at an acute angle to the shaft, 110

while the upper sections of the arms extend in horizontal planes. The spaces between the sections of the several arms are so ranged that the entire set of arms may be folded to lie in a common plane so that the rack when not in use may be folded flatly against the wall.

From the foregoing description and upon reference to the accompanying drawings, it will now be observed that I have provided a relatively simple rack or wall bracket in which the arms are designed to fold in a minimum space and in which the shaft supporting arms are accompanied by an extremely simple form of supporting bracket.

Attention is now directed to the fact that the upper terminal of the lower section 26 of each arm is disposed, when the arms are in folded position, in frictional engagement with the corresponding elements immediately below it. This feature is of importance, since this frictional contact between the lower sections of the several arms serves as a means whereby the arms are yieldably maintained in folded position. Thus, one of the arms may be swung outwardly to extended position and the rest of the arms will remain in folded position.

In reduction to practice, it has been found that the form of this invention illustrated in the drawings, and referred to in the above description as the preferred embodiment, is

the most efficient and practical; yet realizing that the conditions concurrent with the adoption of this device will necessarily vary, it is desirable to emphasize the fact that various minor changes in the details of construction, proportion and arrangement of parts may be resorted to, when required, without sacrificing any of the advantages of this invention, as defined by the appended claim.

What is claimed is;—

A wall rack including a supporting bracket, a vertical axle mounted therein, and a plurality of arms swingingly mounted on the axle, each of said arms being formed from a single length of wire bent to form upper and lower sections which are disposed in a common plane, the arms being of different lengths and having their upper and lower sections spaced from each other different distances whereby all of said arms may be folded to lie in a common plane, the upper terminal of each of the lower sections being disposed, when the arms are in folded position, in frictional contact with that lower section, which lies immediately below it.

In testimony whereof I hereunto affix my signature in the presence of two witnesses.

ELMER G. METCALF.
